PETER COOPER HEWITT, OF RINGWOOD MANOR, NEW JERSEY; THE FARMERS' LOAN AND TRUST COMPANY, EXECUTOR OF SAID PETER COOPER HEWITT, DECEASED, ASSIGNOR TO COOPER HEWITT ELECTRIC COMPANY, OF HOBOKEN, NEW JERSEY, A CORPORATION OF NEW JERSEY.

METHOD OF AND APPARATUS FOR PRODUCING ALTERNATING CURRENTS.

Application filed December 1, 1920. Serial No. 427,485.

The present invention relates to methods of and apparatus for operating and controlling electric devices of the type constituting a gap in a true conductor and comprises new and useful forms of gap devices and new and novel systems of operating and controlling such devices, all of which are useful in the arts generally, and for the production from a direct or varying source of alternating currents, currents of low and high frequencies and of large quantity currents as well as feeble currents, and particularly useful in the signaling art.

5

Further, my invention consists of novel form of gas or vapor or vacuum devices, by which is meant a gap in a true conductor comprising the true conductor terminals and the space between them, which space may consist of as near nothing as is obtainable 10 or of a gas or vapor, or of a mixture of gases or vapors in various degrees of density; that is, the terminals of a true conductor between which there is more or less gas or vapor whose amount may approach 15 zero.

My invention further consists of the control of electric current before and while flowing in a circuit of the character described above.

20 It further consists in controlling the voltage required to pass current and required to maintain current flow in a device of the type above referred to.

It further consists in a circuit associated 25 with the device to facilitate its operation, the whole providing a controlling means for, or means for controlling, an electric circuit.

It further consists in providing means 30 for obtaining a suitable gas or vapor density between the conductor terminals and also in providing means for the support of the conductor terminals inside the vessel.

It further consists in providing means for 35 locating and supporting the shields, for controlling the electric discharge or conducting conditions between, and at a terminal, and the space between the terminals.

I have found that the voltage resistance 40 characteristics of a device or devices of the character referred to above may be controlled by a perforate shield located in close proximity to the positive terminal, where

the solid material of the shield approximates ten per cent (10%) of the area occupied by the perforations and the material bounding them. For example, a perforate solid material having a depth equal to its width works well and it is therefore possible to use wire gauze as a shield material. The 55 action is increased by the use of a multiplicity of shields in parallel and electrically connected. In some instances it may be advantageous that they be connected with varying impedance in their respective circuits.

60 In the accompanying drawings and by way of an example I have illustrated in Fig. 1 a device and circuits showing the general organization of a typical apparatus; Fig. 2 70 is an alternative form of tube for that shown in Fig. 1; and Fig. 3 is a device and circuits with a simple form of control circuit.

Referring to the drawings, Fig. 1, 1 is a 75 tube of the general type referred to above and is shown and described in my application Ser. No. 397,965, filed July 21, 1920. The tube 1 is provided with a positive electrode 2, of wire gauze, or a carbon plate 80 or other suitable material. An active negative terminal is conventionally shown at 3-4 of the mercury type. However, this active negative may be of solid material as shown at 3^a, Fig. 2, and consists of tungsten, 85 tantalum, magnesia mixture or any suitable solid material. In devices of this character it is necessary that the main negative terminal 3 or 3^a be maintained in a conducting condition as by heating a portion of the terminal to incandescence which is accomplished by forming a hot spot on the surface of the terminal by passing current therethrough from a source and circuit conventionally indicated at 23 and 23^a or by 90 heating the terminals to incandescence by other means. The hot spot, above referred to, is accomplished by the lowest resistance for large currents.

95 Current is applied to the tube 1 from a 100 source of direct current 11 through mains 8 and 9, the main switch being shown at 10, a switch shown at 14 being provided for throwing in inductance 15, or resistance 17, as the operator may find necessary in operating the apparatus. An inductive coil 105

29 is located in the positive feed in inductive relation to an inductive coil 16 in a suitable work circuit, in which 18^a represents resistance and 19^a a capacity.

5 In the space between the positive 2 and the negative 3, I mount control shields 5 and 7 of the perforate material, such as wire gauze, of tungsten, molybdenum, or other suitable material, as set forth in my application above referred to, said shields serving as control terminals and functioning to prevent current concentration, thus aiding in the operation of the device. The circuit for the control shields 5 and 7, in this instance, 10 comprises an inductive coil 20 in inductive relation to the coils 29 and 16 of the main circuit and the work circuit, a capacity 31 connected to main cathode 3 by a conductor 35 to the active negative 3 and also connected through a capacity 32 by a conductor 36 to a capacity 30, and by a conductor 37 to the other side of the coil 20. The shields 5 and 7 are connected across the terminals of the coil 20 by the leads 8 and 9, respectively. 15 The shields 5 and 7 are maintained at proper potentials by the batteries 22 and 23 through the conductors 38 and 39, respectively. While the switch 14 in the main line from the source 11 is shown connected directly to said source, I may insert in the line an inductance 15 or resistance 17 to meet requirements of service. There is always some capacity in the circuit which acts as capacity connected from the input lead to coil 29 and negative terminal 3 of the device. In case such capacity is insufficient, it may be increased by a capacity bridged across the main circuit leading to the apparatus. 20 In operation, current is caused to flow through the main negative 3 or 3^a from the battery 23 or 23^a to cause the negative terminal of the device to become active, thus energizing the space between the main terminals 2 and 3 or 2 and 3^a. Battery 23 being connected through the leads 39, 36, 9, to shield 7 is so adjusted as to cause current to flow from shield 7; and battery 22 being connected through lead 38, 37, 8, to shield 5 is so adjusted as to cause current to flow from shield 5. Under certain conditions of operation after such initial flow is established, the voltage of battery 22 may be diminished. 25 The closing of the switch 10 at the source 11 establishes current flow in the main circuit, whereupon current flows through coil 29, terminal 2, to terminal 3, conductor 9, back to source 11. The field established at coil 29 induces current flow in the control circuit due to the inductive relation of the coil 20 to coil 29. The shield 5 is thus given a negative charge which terminates the current flow in the main circuit. The termination of current flow in the main circuit al-

lows the current in the control circuit to reverse or to cease, whereupon current flow in the main circuit through the tube 1 is re-established, again causing the induced current flow in coil 20 to establish a negative charge on the shield 5, terminating current flow in the main circuit. This cycle may be caused to occur at practically any frequency desired, dependent on the electric characteristics of the various circuits. The 75 interlinkage of the main circuit coils and the work circuit coils and the resistance of the work circuit are very important, as well as current-voltage-time-characteristics of the control circuit, in the operation of the device, all of which conform to electric practice. 80

The alternating current generated in the work circuit, due to the interlinkage of the coils 16 and 29, is utilized in said work circuit in a manner now well understood in the art. 85

The device is subject to complete control and therefore may be operated in various ways, circuits and systems. 90

The specific form of my device for producing alternating currents from a direct or varying source is useful in the production of alternating currents of large quantity as well as feeble currents and of practically any frequency and as high as 1,500,000, or higher frequencies. 95

In the system shown, the various circuits may be so adjusted that current normally passes freely through the device 1, but owing to the inductive relation of the coils 16, 20 and 29, an impulse flow in the supply circuit induces current in the control circuit, which current causes a negative charge to the shield adjacent to the positive electrode thereby stopping the flow of current in the main circuit. On the stoppage of current flow the current in the control circuit ceases, whereupon current flow is reestablished in the main circuit which is again terminated by the current in the control circuit, as above set forth, producing currents in the associated work circuit of practically any frequency desired. 105

The operation may be varied by varying 115 the polarity of the current induced in the control circuit, whereupon on current flow in the main circuit the positive current will be present at the shield 5 near the positive 2, but the control circuit being in inductive relation to an oscillatory circuit, or being itself an oscillatory circuit, on the return impulse of the oscillation will have current flow in the opposite direction, which will cause the shield at the positive electrode to be negative 120 and terminate the current flow through the device. This operation will repeat itself successively causing variation in the main current flow. 125

Another operation which may take place 130

is that on initial current flow through the main circuit inductance 20 being reversed will cause shield 5 to be positively charged, but on reversal of the current flow due to 5 either the oscillatory nature of the control circuit to which it is inductively related will cause shield 5 to be charged negatively and interrupt the current flow in the main circuit, whereupon current in the main circuit 10 will start by reason of the persistent oscillation of either the control circuit or the work circuit on shield 5 becoming positive.

When the device is in operation control of current is had by any means moderating or 15 limiting or affecting the electrical action at shield 5, and control is here shown by means of inductance coil 28 operatively associated with a microphone circuit 26 or any source of alternating currents indicated conventionally at 33.

For certain purposes the current flow control by shield 5 is so complete that in certain organizations, such as that shown in Fig. 3, the shield 7 may be omitted and the 25 device operated by means of electric currents applied to shield 5 alone. These currents may be applied from any source whatsoever independent of interaction of coils 20 and 29 and the operation may be performed 30 with devices containing vapors or gases of considerable density as distinguished from high vacuum devices.

While I have described the use of the control shield 5, or the shields 5 and 7, as 35 a means of terminating or moderating the main current flow through the device 1 to produce alternating current from said terminations or said moderations, I prefer for most purposes to cause the shields to terminate the current flow in the operation of 40 the device, as the heating effects within the device will be less.

While I have described the device as a controlled self-controlled generator of alternating currents, it will be understood that 45 the device is useful as a generator of alternating currents controlled from any source.

I claim as my invention:

1. In the production of alternating currents from a direct current or varying current supply source which consists in passing current from said supply between the main terminals of a conducting device having a sealed container and a vaporizable main negative electrode, applying the current flow 50 thus produced to initiate oscillations in a work circuit and in a control circuit co-operatively related to said supply circuit, and applying the oscillations of the control circuit to cause a charge on the current flowing in said conducting device to terminate said current flow, the step of preventing concentration of the current stream between said main terminals which comprises applying the charge from said control circuit 55

substantially uniformly across the discharge path between said main electrodes.

2. In the production of alternating currents from a direct current or varying current supply source by means of an electron discharge device having a main positive electrode, a vaporizable main negative electrode, and a control electrode, the step of preventing concentration of the current stream between said main electrodes which comprises applying a charge from said control electrode substantially uniformly across the discharge path between said main electrodes.

3. In a system of electrical distribution, the combination with a source of electric current, of a conducting device having a sealed container and a main positive and a vaporizable main negative electrode, and a member extending from wall to wall of the device therein and transversely of the current path of said device and serving to prevent concentration of the current flow between said main electrodes, a work circuit inductively related to the supply circuit, and means connected with the supply circuit and with the said conducting device for causing the termination of current flow through said device.

4. In a system of electrical distribution, the combination with a source of electric current, of a conducting device having a sealed container and a main positive and a vaporizable main negative electrode, and a member therein extending across the walls of the device and transversely of the current path of said device and serving to prevent concentration of the current flow between said main electrodes, a work circuit inductively related to the supply circuit, and a control circuit inductively related to the supply and work circuits for 100 causing the termination of current flow through said device.

5. In a system of electrical distribution, the method of operation which consists in passing current from a source of supply 110 between the main terminals of a conducting device having a sealed container, a main negative electrode which is of vaporizable material and through a member therein extending across the walls of the device and transversely of the current path of said device and serving to prevent concentration of current flowing through it and applying to said member a negative charge to terminate said 115 current flow through the conducting device.

6. In a system of electrical distribution, the method of operation which consists in passing current from a source of supply between the main terminals of a conducting device having a sealed container, a main negative electrode which is of vaporizable material and through a member therein extending across the walls of the device and transversely of the current path of said de- 125 130

vice and serving to prevent concentration of current flowing through it and applying the current flow thus produced to initiate oscillations in a control circuit and applying the oscillations of the control circuit to the current flowing in said conducting device to terminate said current flow.

7. In a system of electrical distribution, the method of operation which consists in passing current from a source of supply between the main terminals of a conducting device having a sealed container, a main negative electrode which is of vaporizable material and through a member therein extending across the walls of the device and transversely of the current path of said device and serving to prevent current concentration, creating oscillations in a control circuit and applying the oscillations of the control circuit to the current flowing in said conducting device to modify the main current flow therein.

8. In a system of electrical distribution, the combination with a source of electric current, of a conducting device having a sealed container and a main positive and a vaporizable main negative electrode and a member therein extending across the walls of the device and transversely of the current path of said device and serving to prevent concentration of the current flow between said main electrodes and a control circuit in operative relation to the said member impressing a negative charge on said member for causing the termination of current flow through said device.

9. In a system of electrical distribution,

the combination with a source of electric current, of a conducting device having a sealed container and a main positive and a vaporizable main negative electrode and a member therein extending across the walls of the device and transversely of the current path of said device and serving to prevent concentration of the current flow between said main electrodes and a control circuit in operative relation to the said member impressing a negative charge on said member for modifying the current flow through said device.

10. In a system of electrical distribution, the combination with a source of electric current, of a conducting device having a sealed envelope, a main positive electrode and a vaporizable main negative electrode, a control electrode between said main electrodes of such size and shape as to present across the discharge path between said main electrodes a substantially uniform distribution of control electrode body and of open spaces between parts of said body.

11. In a system of electrical distribution, the combination with a source of electric current, of a conducting device having a sealed envelope, a main positive electrode and a vaporizable main negative electrode, and means for presenting a negative charge between said main electrodes and for distributing current flowing between said main electrodes uniformly across the path of its flow.

In testimony whereof I hereto affix my signature.

PETER COOPER HEWITT.
